UNITED STATES PATENT OFFICE.

GEORGE F. WEISS, OF SPRINGFIELD, ILLINOIS, ASSIGNOR OF ONE-HALF TO FRANK M. McGOWAN AND ROY M. SEELEY, BOTH OF SPRINGFIELD, ILLINOIS.

TIE-TAMPING MACHINE.

1,231,679.

Specification of Letters Patent.

Patented July 3, 1917.

Application filed November 2, 1916. Serial No. 129,091.

To all whom it may concern:

Be it known that I, GEORGE F. WEISS, a citizen of the United States, residing at Springfield, in the county of Sangamon and State of Illinois, have invented a new and useful Tie-Tamping Machine, of which the following is a specification.

This invention relates to machines for tamping dirt or ballast under and against rail-road ties.

The purposes of the invention are: to provide in connection with a car adapted to be propelled on a rail-road track, reciprocating tamping means actuated by a motor on the car and adapted to simultaneously tamp the ballast under and against both sides of the ties and likewise especially adapted to tamp the ballast under and against those parts of the ties which are immediately under the rails, the tamping being done simultaneously in four different directions namely, from both sides of the tie and from both sides of the rail; to provide means for convenient and effective control of the tampers when in use; to provide means for putting the tampers out of commission; to provide means for raising the tampers and supporting them in their raised position when not in use; to provide tampers having relatively slow upward movement and accelerated downward movement, to utilize the full percussive force of the tampers; to provide a machine comprising a plurality of sets of tampers operable separately or jointly; to provide means for propelling the car by the same motor that actuates the tampers; and to provide other novel details of construction hereinafter set forth.

With these ends in view my invention consists in the novel features of construction and combinations of parts shown in the annexed drawings to which reference is hereby made, and hereinafter particularly described and finally recited in the claims.

Figure 1 is a top plan of the machine; Fig. 2 is an enlarged elevation of part of one side of the machine; showing part of one vertical side frame, one lifter-bar, the tamper frame mounted on the lifter-bar, and the means for varying the inclination of the tamper frame relative to the ties; Fig. 3 is an enlarged right-hand end elevation of the machine;

Fig. 4 is a vertical transverse section on the line X. X. of Fig. 1; Fig. 5 is a broken vertical section on the line Y. Y. of Fig. 1; 55 Fig. 6 is an enlarged partial elevation of the left-hand tamper frame and appurtenances, as viewed from the center of the machine looking toward the left; Fig. 7 is an enlarged detail of a part of one tamper 60 frame, a cradle mounted thereon, and means for oscillating the cradle; Fig. 8 is an enlarged transverse section on the line Z. Z. of Fig. 7 looking upward; Fig. 9 is an enlarged transverse section on the line W. W. 65 of Fig. 7 looking downward; Fig. 10 is a broken vertical section on the line V. V. of Fig. 7; Figs. 11 and 12 are respectively an enlarged top plan and an enlarged rear elevation of the main drive shafts and gears; 70 and Fig. 13 is an enlarged detail of the means connecting the wiper shafts with the lifter-bars.

Similar reference characters designate like parts in the different views.

The main frame 1 is preferably of angle bar. The axles 2 are suitably connected with the frame 1. The supporting wheels 3 are loose on the axles, and are gaged to run on the rails of the track. Platforms 4, one 80 at each end of the machine accommodate the operator. Standards 5, 6, and 7 (Figs. 1, 4, 11, and 12) and bearing blocks 8, 9, 10, and 12 are stationary on the main frame.

A shaft 13 is mounted to rotate in suitable 85 bearings on the standards 5 and 6. A similar shaft 14 is mounted to rotate in suitable bearings on the standards 6 and 7.

Intermeshing gear wheels 17 and 18 are secured on the shafts 13 and 14 respectively. 90 A clutch-member 19 is adapted to slide on the shaft 13. A sprocket wheel 20, loose on the shaft 13, has a clutch-member 21 adapted to be engaged by the clutch-member 19 to cause the sprocket wheel to rotate with the shaft. The sprocket wheel 20, is connected to actuate one of the wiper shafts as herein-after described.

A sprocket wheel 22 is secured on the shaft 14. Clutch-members 23 and 24 are 100 adapted to slide on the shaft 14. A sprocket wheel 25, loose on the shaft 14, has a clutch-member 26 adapted to be engaged by the clutch-member 23. A sprocket wheel 27,

loose on the shaft 14, has a clutch-member 28 adapted to be engaged by the clutch-member 24. The sprocket wheel 25 is connected to 5 actuate one wiper shaft as hereinafter described.

The shaft 15 rotates in the bearing blocks 8 and 9. Sprocket wheels 29 and 30 are secured on the shaft 15. The motor 31, preferably a gasolene engine, is suitably located 10 on the main frame. A sprocket chain 33 connects the sprocket wheel 32 on the motor shaft with the wheel 29 on the shaft 15. A sprocket chain 34 connects the sprocket wheel 30 with the sprocket wheel 22 so that the 15 shaft 15 drives the shaft 14 at a reduced speed. The shaft 14 is connected to actuate one set of tampers and the shaft 13 is connected to actuate the other set of tampers. The gear 18 on the shaft 14 meshes with the 20 gear 17 on the shaft 13 to cause the shafts to rotate in opposite directions.

The shaft 16 rotates in the bearing blocks 10 and 12. Sprocket wheels 35 and 36 are secured on the shaft 16. A sprocket wheel 25 37 is connected with the hub of one of the wheels 3. A sprocket chain 38 connects the wheels 27 and 35 so that the shaft 14 drives the shaft 16 at a reduced speed, and a sprocket chain 39 connects the wheels 36 and 30 37 so that the shaft 16 drives the connected wheel 3 at reduced speed.

The clutch-members 19 and 23 are effective to control the operation of the wiper shafts and the clutch-member 24 is effective to control 35 the operation of the car-propelling means. The construction described admits of operating the tampers at a relatively high speed but less than the speed of the motor, and propelling the car at a relatively slow 40 speed and starting or stopping the car as may be expedient.

There are two movable tamper frames 51, one near each end of the machine. Each tamper frame is equipped with means for 45 varying the inclination of the frame relative to the track being operated upon, and is equipped with a plurality of reciprocating tampers, means for actuating the tampers and means for changing the position of the 50 tampers relative to the ties and relative to the rails. Both tamper frames are alike, and on both frames the tampers are alike, the means for actuating the tampers are alike, and the means for adjusting the tampers 55 with respect to the ties and the rails are alike, it is therefore necessary to describe only one tamper frame and appurtenances.

Parallel vertical side frames 40 (Figs. 1, 2, and 3) of approximately arch-shape, are 60 rigid on the main frame. Parallel vertical bars 41 central with respect to the side frames 40 are rigidly secured on the frames. Arch-shape lifter bars 42 turn on pivots 43 on the vertical bars 41.

65 The axis of one pair of pivots 43 is in line

with the axis of the shaft 13 and the axis of the other pair of pivots 43 is in line with the axis of the shaft 14. This relation of the parts serves to prevent slack in the sprocket chains which drive the wiper shafts.

70

Levers 44 are rigidly connected with the lifter bars 42 and are equipped with dogs 45 adapted to engage in notches 46 in the frames 40. Springs 47 surround the levers 44 and act to normally hold the dogs in the 75 notches. Bearing blocks 48 are secured on the lifter bars 42. The lifter bars 42 have arched parts 42' which permit the tamper frames, which project beyond the lifter bars, to move under the arches when they are manipulated by the handle bar 68 to assume different positions indicated by dotted lines in Fig. 2.

80

Each lifter bar 42 is capable of movement independently of the other lifter bars. The 85 wiper shafts 49 are mounted on the pairs of lifter bars respectively. It is at times desirable to change the position of the lifter bars while the tampers are in operation and to effect this it is necessary to provide means 90 pivotally connecting the shafts 49 with the lifter bars 42 so that if one lifter bar be at rest and the other lifter bar of the same pair be raised or lowered, the boxes in which the wiper shaft turns will automatically adjust 95 themselves to the changed position of the shaft.

100

Wiper shafts 49 and 49' are mounted to rotate in boxes 50 (Fig. 13) pivotally connected with the bearing blocks 48. A sprocket wheel 76 is stationary on the shaft 49. A sprocket chain 77 connects the wheels 20 and 76 so that the wheel 21 actuates the wiper shaft. A sprocket wheel 76' is stationary on the shaft 49'. A sprocket chain 105 77' connects the wheels 25 and 76' so that the wheel 25 actuates the shaft 49'.

110

The rectangular tamper frames 51 are preferably of angle iron.

Brackets 52 secured on the tamper frame 110 turn on the wiper shaft and connect the tamper frame with the shaft so that it may turn on the shaft to change the inclination of the tamper bars relative to the ties.

115

Inclined braces 53 (Figs. 3 and 7) rigidly connected with the horizontal rails of the tamper frame give rigidity to the frame.

Each tamper bar is mounted on an oscillating cradle which will now be described. The cradles and the tamper bars mounted 120 thereon are all alike so it is necessary to describe only one cradle and one tamper bar.

125

The cradle comprises two parallel angle bars 54 pivotally connected with the lower rail of the tamper frame and an upper transverse guide-block-support 55 having its ends rigidly connected with the bars 54 respectively.

130

A guide block 56 is mounted to oscillate in the upper guide support 55.

A similar guide-block-support 57 (Fig. 9) is rigidly connected with the lower rail of the tamper frame. A guide block 58 is mounted to oscillate in the lower guide-block-support 57.

The tubular tamper bar 59 slides freely in the guide blocks 56 and 58.

A plate 60 rigidly connected with the tamper bar 59 has at its ends blocks 61 adjacent to the angle bars 54 respectively and the blocks sliding on the angle bars guide the movement of the plate and the tamper bar with which it is connected. Inside of the tamper bar is a coiled spring 65 (Fig. 10) which has one end connected with the tamper bar and the other end connected with the pivot of the lower guide block 58 in such manner that the raising of the tamper bar will stretch the spring and the spring 65 will act to slide the tamper bar quickly downward in the guides.

A plurality of wipers are secured on each wiper shaft. There is one wiper for each tamper bar. Each wiper comprises a hub 62 and a plurality of radial arms 63. When the wiper shaft is rotated the arms 63 will successively engage on the underside of the plate 60 with which it co-operates, to move it upward to cause upward sliding of the tamper bar, and each time that a radial arm lifts the plate and passes it, the spring 65 in the tamper bar will act to slide the tamper bar quickly downward.

To reduce friction and avoid unnecessary wear on the plate 60 each radial arm has at its outer end a little roller 63^a contacting with the lower surface of the plate.

It is obvious that at each rotation of a three-arm wiper, the tamper bar will be lifted and dropped three times. I prefer to use three radial arms for each wiper but a greater or less number of arms may be used.

Shoes 64 are secured at the lower ends of the tamper bars respectively. The shoes of the tamper bars adjacent to each side of the rails have a part cut away so that when the tamper bars are inclined under the rails as indicated by dotted lines in Fig. 3, the tamper bars may be raised without the shoes catching on the base of the rails. The means for inclining the tamper bars under the rails is a feature of great practical value, because it is important that the ballast shall be well compacted immediately below the rails and the construction disclosed is particularly effective for that purpose.

The means for raising or lowering the tamper frames and varying the inclination of the tampers relative to the ties, and the means for effecting the inclination of the tampers with respect to the rails will now be described.

Parallel bars 66 and 66' are connected with the lower rail of the tamper frame by pivots 67 and 67' respectively. A handle

bar 68 has its ends pivotally connected with the upper ends of the bars 66 and 66' respectively. Connecting rods 69 are pivotally connected with the bar 66 and the respective guide blocks 56 of the first pair of tampers on one side of the central tamper bar. Similar connecting rods 69' are pivotally connected with the bar 66' and the respective guide blocks 56 of the first pair of tampers on the other side of the central tamper bar, as clearly shown in Fig. 6. If the handle bar 68 be shifted to the left the connecting rods 69 and 69' will cause the tampers of both pairs to swing to the right and if the handle bar 68 be shifted to the right (Fig. 3) the connecting rods 69 and 69' will cause the tampers of both pairs to swing to the left.

The handle bar 68 may also be used to cause the tamper frame to turn on the wiper shaft, to vary the inclination of the tamper bars with respect to the ties, as indicated by dotted lines in Fig. 2.

Five tampers, that is to say, the central tamper and a pair of tampers on each side thereof are effective to operate between the rails, these tampers all swing in unison to the right or left as the case may be and all operate in unison.

An intermediate bar 70 (Fig. 6) has its ends pivotally connected with the bars 66 and 66' respectively.

Fixed projecting pins 71, one on each side of the guide block 56 of the central tamper bar 59, engage the block to cause the upper end of the central cradle to swing to the left when the bar 70 is shifted to the left and reversely to cause the upper end of the central cradle to swing to the right when the bar is shifted to the right.

A lever 72 is connected with the lower rail of the tamper frame by a pivot 73.

The pair of tamper bars 59 which operate outside of the left-hand rail are connected by a bar 74 having its ends pivotally connected with the guide blocks 56 respectively, and the pair of tampers which operate on the outside of the right-hand rail are connected by a bar 74' which has its ends pivotally connected with the guide blocks 56 of that pair.

A connecting rod 75 connects the lever 72 with the bar 74 and a similar connecting rod 75' connects the lever 72 with the bar 74'.

If the upper end of the lever 72 be moved to the left the lower part of the left-hand pair of tampers will be caused to incline toward the left-hand rail and if the upper end of the lever be moved to the right the pair of tampers on the outside of the right-hand rail will be caused to incline toward the right-hand rail.

At the beginning of the operation of tamping the ballast under the ties, the tampers must descend a greater distance than

when operating near the top of the ties. It is therefore necessary to provide means to adjust the tamper frames to suit the condition of the work. The vertical adjustment 5 of the tamper frame is effected by the levers 44 which raise or lower the lifter bars 42. If the tampers are to operate at the greatest depth, the levers 44 will be set with the dogs 45 in the lowest notch 46 and if the 10 tampers are to operate at a less depth the levers will be raised as indicated by dotted lines in Fig. 2, and set so that the dogs will enter a higher notch. The lifter frames 42 may be raised a notch at a time until they 15 reach the highest position.

Each tamper frame supports a plurality of tamper bars, the tamper bars on one frame constituting one set and the tamper bars on the other frame constituting another set. 20 The sets of tamper bars may be operated separately or together.

The means controlling the operation of the sets of tamper bars and the means controlling the propelling of the machine will 25 now be described.

Horizontal levers 80, 83, and 86 (Fig. 1) are mounted to oscillate on fixed pivots 81, 84, and 87, respectively, and the inner ends of the levers respectively are connected with 30 the upper ends of vertical levers 82, 85, and 88, (Figs. 4, 11, and 12), mounted to oscillate on suitable stationary supports and having at their lower ends forks fitting in the grooves around the clutch-members 24, 23 35 and 19 respectively. If the outer end of the lever 80 be moved to the right, the clutch-member 24 will be caused to slide to the left into engagement with the clutch-member 28 to cause the wheel 27 to rotate 40 and drive the shaft 16, to cause the wheel 36 to drive the wheel 37 to propel the car, and reverse movement of the outer end of the lever will disengage the clutch-members and cause the car to stop.

45 If the outer end of the lever 83 be moved to the left, the lever will cause the clutch-member 23 to slide on the shaft 14 into engagement with the clutch-member 26 of the wheel 25 to cause the wheel to rotate and 50 actuate the right-hand set of tampers.

The moving of the outer end of the lever 86 to the right will cause the clutch-member 19 to slide into engagement with the clutch-member 21 of the wheel 20 to cause the wheel 55 to rotate to actuate the left-hand set of tampers.

When both sets of tampers are in use, two operators, one at each end of the machine, will control the operation of the machine. 60 The operators will use the handle bar 68 to control the inclination of the tamper bars relative to the ties; and will use the levers 72 and the handle bars 68 to control the inclination of the tamper bars relative to the 75 rails; and will use the levers 44 to raise or 80

lower the lifter bars to vary the depth of operation of the tampers, or to raise them entirely above the track when it is desired to propel the machine on the track.

Having fully described my invention what I claim as new and desire to secure by Letters Patent is:

1. In an apparatus of the class described, the combination of a tamper frame disposed above and transverse to the rail of a railway track; tampers mounted on the tamper frame and inclinable in the longitudinal direction of the track and also inclinable in a direction transverse to the track and effective to tamp on both sides of the rail; and means for inclining toward each other the tampers on the opposite sides of the rail. 75

2. In an apparatus of the class described, the combination of tamper frames positioned above a tie and the rails of a railway track; and tamper bars effective to tamp on both sides of the tie and inclinable toward each other transversely of the track, to tamp both sides of the rails. 85

3. In an apparatus of the class described, the combination of tamper frames positioned above a tie and the rails of a railway track; tamper bars mounted on said tamper frames respectively and effective to tamp on both sides of the tie and both sides of the 95 rails; means for inclining the tamper bars on both tamper frames toward the tie; and means for inclining under the rails the two tamper bars adjacent to each rail. 90

4. In an apparatus of the class described, the combination of a tamper frame comprising parallel rails and brace rods rigidly connecting said rails; guide bars pivotally connected with one rail of the tamper frame; a first guide support pivotally connected with 100 said guide bars; a second guide support stationary on one rail of the tamper frame; guide blocks pivotally mounted on the guide supports; a connecting rod pivotally connected with one of said guide blocks; and 110 means for reciprocating said connecting rod. 105

5. In an apparatus of the class described, the combination of a car; a first rotative drive shaft mounted on the car; a second rotative drive shaft mounted on the car and 115 parallel to said first drive shaft; a sprocket wheel on said first drive shaft; a sprocket wheel on said second drive shaft; side frames mounted on the car; a first pair of lifter arms pivotally connected with the side 120 frames in line with the first drive shaft; a first driven shaft mounted on said first pair of arms; a sprocket wheel on said first driven shaft; a sprocket chain connecting the sprocket wheel on the first drive shaft with 125 the sprocket wheel on the first driven shaft; a second pair of lifter arms pivotally connected with the side frames in line with the second drive shaft; a second driven shaft mounted on said second pair of lifter arms; 130

- a sprocket wheel on said second driven shaft; a sprocket wheel on said second drive shaft; and a sprocket chain connecting the sprocket wheel on the second drive shaft 5 with the sprocket wheel on the second driven shaft, all co-acting to rotate the driven shafts during the raising or lowering of the lifter frame.
6. In an apparatus of the class described, 10 the combination of a main frame; a pair of drive shafts mounted on the main frame; a pair of arched lifter bars pivoted in line with one drive shaft; another pair of lifter bars pivoted in line with the other drive 15 shaft; means for supporting the raised lifter bars at different heights above the main frame; tamper frames adapted to oscillate in the arches of the lifter bars; guides on the tamper frames; and tamper bars adapted 20 to slide in said guides.
7. In an apparatus of the class described, 25 the combination of stationary side frames; lifter bars pivotally connected with the side frames; bearing blocks stationary on the lifter bars; boxes pivotally connected with the bearing blocks; wiper shafts adapted to rotate in said boxes; wipers on the wiper shafts; and tamper bars adapted to be actuated by said wipers.
- 30 8. In an apparatus of the class described, 35 the combination of a supporting structure; a pair of arched-lifter bars pivotally connected with the supporting structure; a revoluble shaft mounted on said pair of lifter bars; and a tamper frame mounted on said shaft and adapted to oscillate under the arches of said lifter bars.
9. In an apparatus of the class described, 40 the combination of a supporting structure; a pair of arched lifter bars pivotally mounted on the supporting structure; swiveled bearing blocks on said lifter bars; a rotative shaft mounted in said bearing blocks; a tamper frame mounted to oscillate on said 45 shaft; and means for changing the position of the tamper frame relative to the lifter bars.
10. In an apparatus of the class described, 50 the combination of a supporting structure; two lifter bars pivotally connected with the supporting structure and capable of independent movement; a rotative shaft mounted on and having swivel connections with said lifter bars; a tamper frame supported 55 on said shaft; and tampers on said tamper frame.
11. In an apparatus of the class described, 60 the combination of a supporting structure; lifter bars pivotally connected with the supporting structure; means for supporting said lifter bars in different positions on said structure; a rotative shaft mounted on the lifter bars; a lifter frame oscillative on said shaft; tamper bars mounted to slide and 65 oscillate in said tamper frame; and means 70 controlling the oscillation of the tamper frame on said shaft and the oscillation of the tamper bars on said frame.
12. In an apparatus of the class described, 75 a tamper frame and appurtenances, comprising parallel upper and lower rails; stationary brace bars connecting said rails; guide bars pivotally connected with the lower rail; an upper guide support pivotally connected with said guide rails; a lower 80 guide support stationary on the lower rail; an upper guide block mounted to oscillate in the upper guide support; a lower guide block mounted to oscillate in the lower guide support; and a tamper bar adapted to slide in said upper and lower guide blocks.
13. In an apparatus of the class described, 85 the combination of a tamper frame, comprising upper and lower rails; braces rigidly connecting said rails; guide bars pivotally connected with the lower rail; an upper guide support pivotally connected with said guide bars; a lower guide support in fixed 90 relation to the lower rail; an upper guide block mounted to oscillate in the upper guide support; a lower guide block mounted to oscillate in the lower guide support; a tubular tamper bar adapted to slide in the guide blocks; a cross head connected with the tamper bar and adapted to slide on the 95 guide bars and provided with a projecting plate; means for engaging the plate of said cross-head to raise the tamper bar; and a spring housed in the tamper bar and effective to impel the tamper bar downward. 100
14. In an apparatus of the class described, 105 the combination of a car; two tamper frames mounted to oscillate on axes transverse to the car; means for raising or lowering the tamper frames; means controlling the oscillation of the tamper frames on their axes; tamper bars mounted to slide in said tamper frames; and means for reciprocating said tamper bars.
15. In an apparatus of the class described, 110 the combination of a car; tamper frames mounted to oscillate on axes transverse to the car; means for raising or lowering the tamper frames; means effective to control the oscillation of the tamper frames on their 115 axes, to incline all the tamper bars on one frame in one direction and incline all the tamper bars on the other frame in the reverse direction; tamper bars mounted to oscillate and slide in said tamper frames and 120 positioned to tamp on both sides of the rails; and means for shifting the tamper bars on each frame to incline toward the rails respectively the tamper bars on both sides of each rail. 125
16. In an apparatus of the class described, 130 the combination of a car; a rotative wiper shaft transverse to the car; wipers fixed on said wiper shaft; a tamper frame mounted to oscillate on the wiper shaft; tamper bars

mounted to slide in said tamper frame; and plates connected with said tamper bars and respectively engaged by the wipers on said wiper shaft to raise the tamper bars.

5 17. In an apparatus of the class described, the combination of a car; a rotative wiper shaft transverse to the car; wipers fixed on said wiper shaft; a tamper frame mounted to oscillate on the wiper shaft; tamper bars 10 mounted to slide in the tamper frame; plates connected with the tamper bars and adapted to be respectively engaged by the wipers on said wiper shaft; and springs connected with the tamper bars respectively 15 and effective to impel the tamper bars downward.

ward.

18. In an apparatus of the class described, the combination of a tamper frame, above and transverse to track rails; outside cradles and inside cradles mounted to oscillate on the tamper frame; guides on said cradles; tamper bars adapted to slide in the guides on said cradles; means for oscillating the outside cradles to incline the tamper bars thereon toward or away from the outer sides of both track rails; and means for oscillating the inside cradles to incline the tamper bars mounted thereon toward or away from the inner sides of both track rails oscillating said cradles to incline said tamper bars relative to the rails.

19. In an apparatus of the class described, the combination of a tamper frame above and transverse to the track rails; inside 35 cradles oscillate on the tamper frame above the inner sides of the track rails; guides on the tamper frames; tamper bars mounted to slide in the guides on the inside cradles; outside cradles mounted to oscillate on the 40 tamper frame above the outer sides of the track rails; guides on the outside cradles; tamper bars adapted to slide in the guides on the outside cradles; first cradle-shifting means in operative relation to the outside 45 cradles; connecting devices connecting said first cradle-shifting means with said outside cradles; second cradle-shifting means in operative relation to the inside cradles; and connecting devices connecting said second 50 cradle-shifting means with said inside cradles.

20. In an apparatus of the class described, the combination of a tamper frame above and transverse to the track rails; pairs of inside cradles mounted to oscillate on the tamper frame above the inner sides of the track rails respectively; connecting devices connecting the cradles of each pair; guides on said cradles; tamper bars adapted to slide in the guides on said inside cradles respectively; pairs of outside cradles mounted to oscillate on the tamper frame above the outer side of the rails respectively; connecting devices connecting the cradles of each pair; guides on said cradles; tamper bars

adapted to slide in the guides on the outside cradles respectively; first cradle-shift means in operative relation to the outside pairs of cradles; connecting devices connecting said first cradle-shifting means 70 with the outer pairs of cradles respectively; second cradle-shifting means in operative relation to said pairs of inside cradles; and connecting devices connecting said second cradle-shifting means with said pairs of inside cradles respectively. 75

21. In an apparatus of the class described, means effective to utilize a high speed motor to controllably propel the car at a relatively slow speed, comprising a car frame; car wheels supporting said frame; a motor mounted on the car frame; a rotative first shaft transverse to the car frame; a relatively small sprocket wheel on the motor shaft; a larger sprocket wheel on said first shaft; a sprocket chain connecting said sprocket wheels to rotate said first shaft at slower speed than the motor shaft; a rotative second shaft and a rotative third shaft transverse to the main frame; a relatively small sprocket wheel on said first shaft; a larger sprocket wheel on said second shaft; a sprocket chain connecting said sprocket wheels to rotate said second shaft at slower speed than said first shaft; a third rotative shaft transverse to the main frame; a relatively large sprocket wheel on said third shaft; a smaller sprocket wheel loose on said second shaft; a clutch on said second shaft engaging the sprocket wheel on said shaft to cause it to rotate with the shaft; a sprocket chain connecting the sprocket wheel on said second shaft with the sprocket wheel on said third shaft to rotate the third shaft at a slower speed than said shaft; a relatively small sprocket wheel on said third shaft; a relatively large sprocket wheel connected with one car wheel; and a sprocket chain connecting the smaller sprocket wheel on said third shaft with the sprocket wheel connected with said car wheel, to rotate the car wheel at a slower speed than said third shaft.

22. In a tie-tamping machine, the combination of a motor; first, second, and third, 115
rotative drive shafts in operative relation to the motor; sprocket gears and a chain connecting the first and second drive shafts and adapted to rotate the second drive shaft at reduced speed; sprocket wheels loose on 120
the second and third drive shafts; clutches adapted to engage said loose sprocket wheels; means for operating the clutches selectively; intermeshing gears adapted to 125
rotate the third drive shaft in unison with the second drive shaft; first and second wiper shafts on opposite sides of the second and third drive shafts; sprocket gears and a chain connecting the first wiper shaft with 130
the second drive shaft; sprocket gears and 135

a chain connecting the second wiper shaft with the third drive shaft; sets of wipers on the respective wiper shafts; and tamper bars adapted to be lifted by the wipers; all 5 co-acting to controllably rotate both sets of wipers, or either set of wipers, at a speed slower than the rotative speed of the motor.

23. In a tie tamping machine, the combination of a car adapted to run on a track; 10 tamper frames oscillative on axes transverse to the car; and reciprocable tamper bars mounted on the tamper frames and variably inclinable in the longitudinal direction of the track and also inclinable in directions 15 transverse to the car.

Copies of this patent may be obtained for five cents each, by addressing the "Commissioner of Patents, Washington, D. C."

24. A tie tamping machine comprising a main structure movable in the longitudinal direction of a railway track, and tampers inclinable in the longitudinal direction of the track to tamp on both sides of the ties 20 and inclinable in the transverse direction of the track to tamp on both sides of the rails.

In witness whereof, I have hereunto signed my name at Springfield, Illinois, this 28th day of June, 1913.

GEORGE F. WEISS.

Witnesses:

JOSEPH S. THOMPSON,
MYRA THOMPSON.
